UNITED STATES PATENT OFFICE.

EDGAR M. CLARK, OF NEW YORK, N. Y., ASSIGNOR TO STANDARD DEVELOPMENT COMPANY, A CORPORATION OF DELAWARE.

REFINING OF PETROLEUM OIL.

No Drawing.

Application filed July 3, 1919. Serial No. 308,646.

To all whom it may concern:

Be it known that I, EDGAR M. CLARK, a citizen of the United States, residing at New York, in the county of New York and 5 State of New York, have invented a new and useful Improvement in the Refining of Petroleum Oil, of which the following is a specification.

The present invention relates to the art 10 or refining petroleum oil, and will be fully understood from the following specification.

In the ordinary method of refining petroleum oil for the production of marketable products therefrom, it is common to 15 treat the oil with sulphuric acid which is known to have the power of reacting on certain impurities or undesirable constituents of the oil, notably sulphur compounds 20 present. As the percentage of sulphur in the oil increases, it becomes necessary in general to employ greater quantities of sulphuric acid, with a resultant large increase in the refining loss. With oil of a 25 poor quality the refining loss involved in an acid treatment adequate for the production of a marketable refined oil may become so high that refining is no longer a profitable operation.

30 In accordance with the present invention there is provided a new method of refining by which a marketable product conforming to standard specifications may be produced from an inferior crude oil distillate 35 with a minimum refining cost and loss.

The manner of practising the present invention will be apparent from the following example:

30 The oil to be refined is a heavy cut produced by rerunning a distillate produced from a Mexican fuel oil by the pyrogenetic decomposition process described in the patent of Wm. M. Burton, No. 1049667 of January 7th, 1913. It has a gravity of 44.7° B. 45 and a sulphur content of .477% as determined by the combustion method.

50 This oil is first treated with 20 pounds per 40 gallon barrel of 66° sulphuric acid as a result of which there is obtained a treated product representing 91.5% of the original oil and having a gravity of 44.3° B. and a sulphur content of .333%. It will therefore be observed that this first acid

treatment slightly decreased the Baumé 55 gravity and substantially decreases the sulphur content with a refining loss of 8½%.

The product of this first acid treatment is now washed, neutralized and redistilled with fire and steam, and divided into three 60 fractions. The first fraction constituting 28.34% of the treated oil is a heavy naphtha having a gravity of 52.5° B. and a sulphur content of .066%. The second fraction 65 which constitutes the remainder of the distillate is the kerosene or burning-oil fraction; represents 52% of the treated oil, has a gravity of 44.5° B. and sulphur content of .175%. The third fraction which represents the undistilled residue or bottom 70 amounts to 20% of the treated oil, has a gravity of 34.7° B. and a sulphur content of 1.132%.

With respect to the products obtained by 75 redistilling the treated oil, it will therefore be observed that the sulphur content of both of the distilled fractions is markedly below that of the treated oil while the sulphur content of the undistilled residue 80 or bottom is not only higher than that of the treated oil, but substantially above that of the untreated oil. It therefore appears that the effect of the acid treatment is not only to cause the direct elimination in the acid sludge of the sulphur compounds of 85 the oil, but to substantially increase the boiling point of other sulphur compounds which are not actually eliminated by the treating operation, permitting their elimination by a 90 subsequent distillation. That this result is in fact due to the reaction of the acid is confirmed by the fact that a distillate from the untreated oil having substantially the 95 same gravity as the bottom of distillation from the treated oil (i. e. 34.6° as against 34.7°) shows a sulphur content of only .805 as against 1.132, for the bottom from the treated products. The middle fraction of 100 the treated and redistilled oil produced as above described and having a gravity of 44.5°, sulphur content of .175, is now again treated with 20 pounds per 40 gallon barrel of 66° sulphuric acid. As a result of this 105 second treatment there is obtained an oil with a gravity of 44.5° and sulphur content of .10%, and representing 44.72% of the original untreated oil, the refining loss of

this second treatment having been 5.44% of the original oil.

The product of the second acid treatment is again redistilled with fire and steam, producing 90% of distillate and 9.7% of bottoms, or undistilled residue, the distillation loss being .13%. The 90% distillate, representing 40.25% of the original untreated oil, has a gravity of 45.1° and sulphur content 10 of .056 which is well within standard limits for a burning oil of good quality. The bottoms of this second distillation have a gravity of 37.2° and a sulphur content of .585, thus again demonstrating the 15 found effect upon the boiling point of the sulphur compounds in the oil resulting from the acid treatment.

The foregoing represents the nature of the procedure to be followed in practising the present invention. In general this procedure consists in the division of the treating process into a plurality of steps by which means advantage is taken of the profound modification of the boiling point of 20 the sulphur compounds which are not actually eliminated or thrown down into the sludge by the acid treatment. As a result of this procedure there is a marked economy in the use of acid and in the refining loss 25 as represented by the sludge produced. There is necessarily involved the slight loss resulting from redistillation, but this is quite negligible as compared with treating losses.

In the foregoing example I have given a particular application of the method in which the proportion of acid employed in the two treatments is the same. This is by 30 no means necessary, however, but is to be governed solely by the exigencies of the particular situation in which the refiner finds himself, as for example, in dealing with an oil of substantially the same characteristics, that is a fraction of a pyrogenetic 35 distillate from Mexican petroleum having a gravity of 45.6° and a sulphur content of .441%. I may proceed as follows:

The first acid treatment is with 15 pounds 40 per 40 gallon barrel of 66° acid. This gives a refining loss of 3.4% and a treated oil of gravity 45.7°, sulphur .347%. Upon redistillation, as before, there is obtained a naptha fraction of 38.88% of the treated oil, gravity 51.8°, sulphur .145, and a kerosene 45 fraction representing 41% of the treated oil having a gravity of 44.9°, sulphur con-

tent of .244, and a 20% bottom of a gravity of 36.4°, sulphur .891.

The kerosene fraction of the treated oil is again treated, this time with 20 pounds 50 per 40 gallon barrel of 66° acid, giving a refining loss of 8.79%, the treated product having a gravity of 46.2°, sulphur content .162. This product of the second treatment is redistilled, leaving a bottom of approximately 10% having a gravity of 35.3° and sulphur content of .961. The distillate representing 90% (31.43% of the original oil) has a gravity of 45.6° and a sulphur content of .067. 70

While I have in the foregoing described in considerable detail two specific processes in accordance with my invention, it will be understood that these are illustrative only and for the purpose of making clear 75 the principle and mode of operation of the invention and that I do not regard my invention as limited to the precise processes described, nor to any detail thereof, except in so far as such limitations form a part of 80 the accompanying claims in which it is my intention to claim all novelty inherent in the invention as broadly as is permissible in view of the prior art.

What I claim as new and desire to secure 85 by Letters Patent is:

1. The method of refining petroleum distillates of high sulphur content which consists in treating the same with 66° Baumé sulphuric acid, separating the treated oil, 90 redistilling to leave a bottom of high sulphur concentration, again treating the distillate with 66° Baumé sulfuric acid and redistilling as before, whereby there is obtained a distillate of minimum sulphur content with a minimum refining loss. 95

2. The method of refining a distillate of Mexican crude petroleum of the class of kerosene or burning oil, having a high sulphur content of approximately 0.45%, 100 which consists in treating the same with 66° Baumé sulphuric acid and redistilling the treated oil with the elimination of a bottom of approximately 20% of high sulphur concentration, again treating the distillate with 105 66° Baumé sulphuric acid and redistilling the product of the second treatment to eliminate a second bottom of relatively high sulphur content and to produce a final distillate of low sulphur content. 110
